UNITED STATES PATENT OFFICE.

EMIL TYDEN, OF EVANSTON, ILLINOIS.

BAG-TIE SEAL-LOCK.

1,396,479.

Specification of Letters Patent.

Patented Nov. 8, 1921.

Application filed January 6, 1921. Serial No. 435,404.

To all whom it may concern:

Be it known that I, EMIL TYDEN, a citizen of the United States, and resident of Evanston, in the county of Cook and State 5 of Illinois, have invented certain new and useful Improvements in Bag-Tie Seal-Locks, of which the following is a specification, reference being had to the accompanying drawings, forming a part thereof.

10 The purpose of this invention is to provide an improved device for securing a bag-tie adapted to be sealed or secured by a flangible or rupturable seal, so that the tie cannot be released without breaking or 15 rupturing the seal. It consists in the elements and features of construction shown and described, as indicated in the claims.

In the drawings:—

Figure 1 is a side elevation of a bag having a tie provided with the locking and sealing device embodying this invention.

Fig. 2 is a top plan view of the tie securing and sealing device with the cords or tie therein and secured at sealed position.

25 Fig. 3 is a section at the line, 3—3, on Fig. 2.

Fig. 4 is a section at the line, 4—4, on Fig. 3.

Fig. 5 is a perspective view of the cord-clamping, seal-holding device with its several parts separated.

Fig. 6 is a section at the line, 6—6, on Fig. 3.

In the drawings, A represents the bag to be tied, B the cord or tie which secures it by constricting it at the mouth in the usual manner; C is the base member of the tie-sealing device. This member comprises three pieces, the main plate 1, which is designed to be stamped from a metal sheet or thin plate having longitudinal flanges, 1^a, for stiffening it, having at one end an upturned lip or flange, 1^b, turned longitudinally outward for a short extent at 1^c, to 40 form a shoulder for lodgment of the latch as hereinafter explained, then turned upward at 1^d, to furnish a guard for the end of the latch, then folded back over the shoulder or seat, 1^e, for retaining the latch as 45 hereinafter explained, the final lip, 1^f, having struck down from it at one end a short lug, 1^g, to furnish a stop for the swinging movement of the latch to sealing position. The lip or flange, 1^b, has two cord apertures, 1^h, through which the cord may extend 50 under the seat or shoulder, 1^e. At the other

end of the base plate, 1, there is mounted a second piece, 2, of the base member which is a U-shaped part having two upstanding flanges, 2^a, 2^b, provided with two cord apertures, 2^b, alined with the corresponding cord apertures, 1^g. This piece, 2, is secured to the main piece, 1, by being lodged between the longitudinal flanges, 1^a, 1^a, which are clenched down onto the lateral edges of the neck of the U member, as seen at 1^h. The third piece of the base member, C, is a label or tag holder, 3, being a thin metal plate having a rectangular aperture, 3^a, and longitudinal in-turned lips, 3^b, forming flanges 70 which may meet substantially at the longitudinal middle line, rendering said part, 3, substantially tubular, and affording means for securing said tubular member upon the back or under side of the part, 1, by any 75 convenient means, as soldering or spot-welding.

5 is a cord-clamping saddle which is a piece of metal plate folded to form parallel flanges, 5^a, spaced apart so that the saddle 80 enters and fits loosely between the two parallel flanges, 2^a, 2^b, of the part, 2, said flanges, 5^a, having cord-striding notches, 5^b, positioned for alinement with the cord apertures, 2^b, of the part, 2, when the saddle is 85 entered between said flanges, 2. A stud, 6, rigid with the base plate, 1, positioned centrally in the rectangular space defined by the flanges, 2^a, 2^b, of the piece, 2, serves to position the cord clamp, 5, the latter having 90 a central aperture for engaging said stud.

7 is a latch member pivoted upon the stud, 6, under the head thereof, and thereby held into close relation with the upper edges of the flanges, 2^a, 2^b, in the swinging movement which the said latch may have about said pivot stud. The cord clamping saddle member, 5, has two upwardly projecting bosses, 5^c, 5^d, and the latch member, 7, has two recesses, 7^e, 7^f, said bosses and said recesses being at diametrically-opposite positions in the respective parts with respect to the pivot stud or axis of the latch, and said bosses and recesses coöperate in a cam action for clamping the saddle onto the cord extending between the two flanges, 2^a, 2^b, of the piece, 2. The latch member, 7, is of such length from its pivot on the stud, 6, that its remote end enters closely behind the guard flange, 1^d, and under the retaining 100 flange or lip, 1^e, and is stopped against the lug, 1^g. Said latch has longitudinal flanges,

7^e, folded up and over toward each other to make substantially a tube or sleeve for receiving a seal consisting of a flat strip of metal which may be inserted longitudinally therethrough; and at the stopped position of the latch against the lug, 1^f, said tube or sleeve registers with a seal aperture, 1^j, of the guard flange, 1^a. At this position of the latch the cam projections, 5^e, of the clamping saddle, 5, have been crowded out of the recesses, 7^e, by the rotation of the latch, and the saddle has been clamped down tightly upon the cord, B, engaged in its cord-striding notches.

15 Any form of seal consisting of a strip which can be inserted through the seal tube or sleeve, 7^d, and the seal aperture, 1^j, and provided with means or features of construction which prevent it from being withdrawn or pulled on through, may be employed to secure the latch at cord-striding position so that it cannot be released to release the cord without rupturing the seal.

In the drawings there are shown two familiar forms of seals which may be employed in this device, the first being a familiar type consisting of a thin strip or tape, F, having at one end a sealing bulb, F¹, through which the free end of the strip is inserted after it has been passed through the sleeve and seal aperture. This form of seal is familiar and needs no specific description of its own construction. In Fig. 2 there is shown another form of seal consisting of a strip of metal G, adapted to be inserted through the sleeve and seal aperture, having at one end a cross-head, G¹, which may be drawn up closely against the outer side of the guard, 1^a, the other end portion of the strip which projects beyond the sleeve being weakened by scoring or apertures at a transverse line which stands at the inner end of the seal tube or sleeve when the cross-head of this seal is against the guard, 1^a, the method of sealing being to fold back the protruding end portion of the seal onto the seal tube or sleeve, the metal of the seal being such that it cannot be unfolded without breaking at the scored or weakened cross line. This form of seal is also familiar and the seal in either form constitutes no part of the present invention.

When the form of seal last described is to be employed, it will be found desirable to provide a slip ring, 10, on the seal sleeve or tube, which can be slipped over the reversed end of the seal to prevent the latter from becoming accidentally engaged, and thereby folded back or broken. When this slip sleeve is employed, it is retained on the seal sleeve or tube by a slight boss, 1^m, lug struck down from the back side of the tube, as seen at 7^e, the slip sleeve being adapted to spring over this boss when entered upon the sleeve at the open end and the slip sleeve has an aper-

ture, 10^a, which snaps into engagement with the boss for positioning the slip sleeve at the proper position along the length of the seal tube or sleeve for masking the end of the reflexed seal and preventing it from being accidentally engaged. When the properly authorized person desires to release the tie, the slip sleeve will be readily pulled back from off the end of the seal and the latter can then be reflexed for breaking it.

75 For securing a tag or label which may be inserted in the tag slide-way, against accidental or intentional removal so long as the tie is locked, the base has an aperture, c³, and a clamping saddle, 5, provided with a lug 80 or finger, 5^a, extending in said aperture and long enough to extend across the open end of the tag or label-holding space in the tag holder, 3, when the said clamping saddle is forced into cord-gripping position by the 85 closing of the latch.

When the cord to be gripped by the clamping jaw is very hard or glazed, as is sometimes the case with new cord, slipping is not impossible, notwithstanding the grip of the 90 cord clamp upon it, so that it may be possible without tearing it to draw it through the jaws sufficiently to release the tie. To provide against this possibility there may be provided an additional gripping device, having a more positive engagement with the cord, and one which if operative at every 95 instance of clamping, would deteriorate the cord, but which will be unobjectionable if it only comes into operation when an attempt is made to force the cord through the clamping jaw. Such a device is shown at 8, consisting of a U-shaped member having its U-limbs or flanges, 8^a, serrated for engaging the cord. This U-shaped member has a 100 central aperture by means of which it is lodged upon the pivot stud, 6, under or behind the clamping saddle, with its said serrated flanges facing in the opposite direction from the saddle wings or flanges, 5^a, and 105 between said flanges respectively, and the flanges, 2^a, of the base. The serrated flanges 8^a, of the part, 8, are of such height or width that the serrated edges project into the straight-line path of the cord when 110 stretched taut from the gripping edges of the flanges, 5^a, through the cord apertures of flanges, 2^a. From this relation of the parts it results that when stress is applied to the cords in an attempt to pull them through 115 the gripping device, they are thereby drawn onto the serrated edge of the part, 8, and gripped positively by said serrations, so that said cord cannot be pulled through without tearing it by the serrations.

120 I claim:—

1. In combination with a base having the cord runway, a clamping jaw carried by the base opposite the cord runway; a latch adapted at one position to be locked to the 125 130

base, having a cam for clamping the jaw onto the cord in the runway by the swinging of the latch to locking position, the base and the latch having seal-accommodating passages which are registered at cord-clamping position, and a seal which is introducible into said passages transversely of the cord-releasing movement of the latch, and means defeating the withdrawal of the seal unruptured.

2. In the structure defined in claim 1, foregoing, the latch being pivoted for swinging in the plane of the seat of the seal therein, the base having a guard behind which the free end of the seal seat of the latch swings for clamping the cord, said guard having a seal passage which registers with the seal passage of the latch; whereby the seal is opposed edgewise of the cord-releasing movement of the latch.

3. In combination with a base and means for seating and clamping the cord therein, said means comprising a rotatable cam-carrying member, said member having a seal-holding tube or sleeve open at both ends, the base having a guard projection behind which one end of the seal tube stands at cord-clamping position, said guard having a seal aperture registered at said position with the seal tube.

4. In combination with a base having a plurality of spaced-apart up-standing lips or flanges provided with cord apertures; a clamping saddle having flanges spaced to fit loosely between two consecutive flanges or limbs of the base, and having cord-striding notches positioned for registering with the cord apertures of said flanges; a latch device pivoted between the said two flanges of the base for swinging in a plane transverse to the direction of projection of said flanges, the clamping saddle being apertured for mounting on said pivot and for moving there-along in its clamping action, and co-operating cam depressions and projections in the saddle and the latch for clamping

the cord in the swinging movement of the latch.

5. In combination with the structure defined in claim 4 foregoing, a slide on the seal-seating sleeve, adapted to mask a reverse seal end, and means for yieldingly engaging it with the sleeve at seal-masking position.

6. In the construction defined in claim 4, foregoing, a serrated member for engaging the cord, positioned between the clamp and the flange which has the cord aperture, with its serrated edge projecting into the straight-line path of the cord when stretched taut from the cord aperture to the saddle notch.

7. In the construction defined in claim 4, foregoing, a U-shaped member lodged on the latch pivot under the saddle and having its U-limb or flange projecting between the saddle limbs respectively and the adjacent flanges of the base, said U-limbs or flanges being serrated and protruding into the straight-line path of the cord when stretched taut from the cord apertures to the saddle notches respectively.

8. In combination with a base having a cord runway, a clamping jaw carried by the base opposite the cord runway; a latch adapted at one position to be locked to the base, and having means for clamping the jaw onto the cord runway by its movement to that position; the base having at the opposite side from that at which the clamping jaw is situated a tag-receiving slide-way whose end open for entering the tag thereinto is substantially even with the end of the base at which the clamping jaw is situated, said clamping jaw having a projection which is thrust across said opening to bar the escape of the tag by the cord-clamping movement of said clamping jaw.

In testimony whereof, I have hereunto set my hand at Chicago, Illinois, this 3rd day of January, 1921.

EMIL TYDEN.
